UNITED STATES PATENT OFFICE.

JOHN G. WHILLDIN, OF PHILADELPHIA, PENNSYLVANIA.

DESIGN FOR A FLOWER-POT.

SPECIFICATION forming part of Design No. 19,280, dated August 20, 1889.

Application filed July 12, 1889. Serial No. 317,932. Term of patent 14 years.

To all whom it may concern:

Be it known that I, JOHN G. WHILLDIN, a citizen of the United States, and a resident of Philadelphia, in the county of Philadelphia and State of Pennsylvania, have invented certain new and useful Designs for Flower-Pots; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a side view; and Fig. 2 is a bottom view.

This invention has relation to designs for flower-pots; and it consists in the novel form and configuration of the parts thereof, as hereinafter set forth.

In the accompanying drawings, illustrating this design, the letter A designates the body of the pot, which is in the form of an inverted

frustum of a cone, which is slightly convex from below upward. Joined to this conical body portion A by an exterior annular shoulder B is the marginal re-enforcement C, or band portion around the mouth of the pot, said band portion or re-enforcement being also conical, but of very high degree, approaching the cylinder. The bottom of the pot is formed with notches of escalloped form, as at D.

What I claim is—

The design for flower-pots, consisting of the conical frustum-body portion A, having the escalloped bottom, and the marginal re-enforcement or band portion C, joined to said body portion by the exterior annular shoulder B, substantially as specified and shown.

In testimony whereof I affix my signature in presence of two witnesses.

JOHN G. WHILLDIN.
